UNITED STATES PATENT OFFICE.

AUGUSTE DACCORD, OF PHILADELPHIA, PENNSYLVANIA.

SHOCK-ABSORBER.

1,195,979.

Specification of Letters Patent. Patented Aug. 29, 1916.

Application filed March 28, 1916. Serial No. 87,162.

To all whom it may concern:

Be it known that I, AUGUSTE DACCORD, a citizen of Switzerland, residing at Philadelphia, in the county of Philadelphia and 5 State of Pennsylvania, have invented certain new and useful Improvements in Shock-Absorbers, of which the following is a specification.

The invention relates to certain new and 10 useful improvements in shock absorbers adapted to serve alone as the spring device or as an auxiliary to another spring device. While primarily intended for vehicles, it may be employed to cushion and absorb 15 shocks occurring between any two relatively moving parts.

The primary object of the invention is to provide means for resiliently resisting forces applied between two parts and at the 20 same time to retard the action of the forces and resistance thereof.

With these and other objects in view as will be hereinafter pointed out, reference will be had to the accompanying drawing 25 forming a part of this specification and wherein like characters of reference designate corresponding parts throughout the several views, in which:

Figure 1 is a vertical sectional view 30 through the invention, Fig. 2 is a similar view taken at right angles to Fig. 1, Fig. 3 is a view in elevation of an upper fragment of the invention, and Fig. 4 is a view in elevation of a lower fragment of the invention.

The invention comprises a body portion composed of front, rear, and end walls, 1, 2, 3 and 4, respectively, said walls being provided with a dome cover member 5. The front wall is extended upwardly to provide an 40 arm 1' and the rear wall is similarly extended to provide a similar arm 2'. Extending upwardly from the cover member 5 are arms or wall portions 1'' and 2'', the wall portion 1'' being spaced from and connected in 45 parallel relation with the arm 1' by connecting parallel spaced wall portions 1^a and 1^b, and in a similar manner and by similar means, the walls 2' and 2'' are connected. The cover member does not extend across 50 the spaces between the wall portions and arms 1'' and 1' or 2'' and 2'. A bolt 6 ex-

tends through arms 1', 2' and wall portions 1'' and 2'' and is rigidly held by suitable means therein, and to this bolt one of the vehicle springs is attached. The other or 55 complementary vehicle spring is attached to a second bolt 7, which extends through the members 1', 1'', 2', and 2'' and works up and down in vertical slots 8 formed therein. The outer ends of this bolt 7 are suitably secured in plungers 9, one of said plungers being vertically slidable between members 1' and 1'', and the other between members 2' and 2'', and each plunger 9 is provided with a vertical slot 10 through which the 60 said bolt 6 extends. At their lower ends, these plungers 9 are provided with heads 12, and these heads are connected together for simultaneous movement by bolts 14, 15, said bolt 7 serving a similar purpose. A pair of 70 toggle links 16, 17 are pivotally secured to the bolt 14 and similar links 18 and 19 are pivotally secured to the bolt 15, and the said heads 12 occur between said links and the front and rear walls 1 and 2 respectively of 75 the housing. The lower ends of the links 16 and 17 are pivotally connected by means of a bolt 20 with toggle links 21 and 22, and the lower ends of the links 18 and 19 are pivotally connected by means of a bolt 24 80 with toggle links 25 and 26; and the links 21, 22, 25, 26 are pivotally connected by means of a bolt 27. The links 25 and 26 occur between the front and rear housing walls 1 and 2 and the other links, while only 85 the upper portions of the links 21 and 22 occur between said front and rear walls and the links 16 and 17, due to the said links 21 and 22 being off-set at their lower ends as indicated by numeral 28, so that the lower 90 portions 21' and 22' of said links 21 and 22 respectively, come between the lower ends of the links 25 and 26. The bolt 27 has no movement and its ends pass through the front and rear housing walls 1 and 2 respectively and through an encircling reinforcing band 30, one end of said bolt having a head 27' and the other end being threaded 95 to receive a nut 27".

A coil spring, substantially rectangular in 100 cross section, and indicated by numeral 31 is arranged horizontally within the housing,

and each end of said spring is provided with a pair of loops 32, each loop bent from a terminal side strand of the spring 31. The bolt 20 extends through the pair of loops at one end and the bolt 24 extends through the pair of loops at the other end of the coil spring 31. A buffer spring is provided for each of the bolts 20 and 24, each buffer spring being composed of parallel free end portions 35 which are bent inwardly at 36 and coiled at 37 to form eye portions, then bent outwardly at 38 into the plane of said portions 35, the said portions in said plane being connected by a loop portion 39. The bolt 20 passes through the eye portions 37 of one of the buffer springs, and the bolt 24 passes through the eye portions 37 of the other buffer springs. The terminal ends 35 and looped end 39 of one of the buffer springs 20 bear against the inner face of the wall portion 3, while the terminal ends 35 and looped end 39 of the other buffer spring bear against the inner face of the wall portion 4. For the purpose of repair, upon removing the bolt 27, the internal parts may be withdrawn as a unit from within the housing through the open lower end thereof.

In operation, whether force is applied to move the bolt 6 toward the bolt 7 or vice versa, or whether such force is applied through vehicle springs or other mediums, the relative movement between the parts is as follows: The bolt 7 moves vertically within the slots 8 and the bolt 6 moves vertically within the slots 10, and the plungers 9 move vertically, downwardly. With the downward movement of the plunger heads 12 within the housing, the toggle links exerting resisted force against the stationary bolt 27 are caused to spread to force the bolts 20 and 24 away from each other, which spreading apart of said bolts is resisted by the tension spring 31, and also by the buffer springs between said bolts 20 and the adjacent walls of the housing. As these bolts 20 and 24 move toward the adjacent walls of the housing, each buffer spring tends to flatten out against its respective housing wall, and in such flattened condition slides vertically along said housing wall and serving in that manner as a friction retarder. Thus the force applied to the bolt 6 or 7 is not only resisted by the springs, but the resisting action is also combined with a retarding action due to the buffer springs sliding along the walls of the housing, and this retardation not only takes place upon the downward movement of the plungers, but also upon the upward movement thereof.

What is claimed is:

1. In a device of the character described, a housing, a plunger therein, links between the housing and plunger adapted to spread apart, and means pivotally connected with

said links and frictionally engaging the housing to resist and retard such spreading apart action of the links.

2. In a device of the character described, a housing, a plunger therein, links between the housing and plunger adapted to spread apart, and springs pivotally connected with said links and frictionally and slidably engaging said housing to resist and retard the spreading apart action of the links. 75

3. In a device of the character described, a housing, a plunger therein, links between the housing and plunger adapted to spread apart, and springs pivotally connected with said links and having their opposite end portions slidably engaged with the housing to resist and retard the spreading apart action of the links. 80

4. In a device of the character described, a housing, a plunger therein, links between the housing and plunger adapted to spread apart, tension means between said links resisting spreading apart of the links, and springs pivotally connected with said links and frictionally and slidably engaging said housing to resist and retard spreading apart of the links. 85

5. In a device of the character described, a housing, a plunger therein, links between the housing and plunger adapted to spread apart, a coil spring between said links and having its opposite ends connected therewith to resist spreading apart of the links, and springs pivotally connected with said links and arranged between said links and housing and having their opposite end portions bent toward and engaging the housing, said engaging end portions having frictional sliding engagement with the housing in a line substantially at right angles to the line of spreading action of said links. 95 100

6. In a device of the character described, a housing, a pair of plungers therein, parallel sets of links pivotally connecting the lower ends of said plungers with the lower end portion of the housing, the links of each set being adapted to spread apart, a coil spring between the sets of links and connected with the links of each set to resist spreading apart of the links of each set, and retarding buffer springs between the housing and each set of links. 105 110 115

7. In a device of the character described, a housing, a pair of plungers slidably arranged therein, a removable bolt extending across the lower portion of the housing, and links connecting said bolt and plunger, the links being arranged in two parallel sets, the links of each set being adapted to spread apart, a coil spring between the two sets of links and serving to resist the spreading apart action of the links, and buffers pivotally connected with said links and slidably engaging the housing. 120 125

8. In a device of the character described, 130

a housing having an open lower end, a bolt extending across the lower portion of the housing, four links pivoted to said bolt, a pair of bolts each connecting two of said 5 links together, a pair of links pivotally connected to each of said last mentioned bolts, plungers to which the last pairs of links are pivotally connected, said plungers being slidably arranged in the housing, a coil spring arranged between and having its 10 opposite ends connected with said pair of bolts, and a pair of buffer springs pivotally connected with said same pair of bolts and having their opposite ends slidably and yieldingly engaged with the housing. 15

In testimony whereof I affix my signature.

AUGUSTE DACCORD.
